UNITED STATES PATENT OFFICE.

JOSEPH A. CUNNINGHAM, OF PHILADELPHIA, PENNSYLVANIA.

THEATER APPLIANCE.

Application filed August 5, 1924. Serial No. 730,224.

This invention embodies improvements in theater appliances, and is more particularly adapted for use in staging illustrations of scenic changing games or the like.

5 The primary object of the invention has been to devise a suitably arranged and conveniently mounted combination of coacting elements, functioning as a mechanically associated removable stage setting for a performer in enacting a uniquely novel form 10 of entertainment, as a pantomime short act or otherwise, illustrating a game of golf or the like, whereby the motions of the performer as the ball driving strokes are 15 made, which actions may be of a highly instructive character, and the movements of the performer together with the changing of the scenery, as the performer supposedly traverses the course, are all visualized in 20 a more truly realistic and pleasing manner, in simulation of an actual game.

The foregoing and other objects, aims and advantages, however, as well as the novelly combined means for attaining the same, will 25 all be so clearly apparent it is believed, as incidental to the following disclosure, that it would serve no useful purpose to further enlarge upon the same initially, and with these prefacing remarks, therefore, reference 30 will now be immediately had to the accompanying drawings, illustrating a practical embodiment of the improvements.

The single figure of the drawings is a 35 perspective view of an illustrative form of the improved apparatus, which is adapted for association with a suitably dimensioned opening in a forwardly located stage curtain, or the like, that is omitted from the drawings for clearer illustration.

40 From a broader aspect, the improvements embody a horizontally disposed movable platform, functioning reversely to a tread-mill-like action, as associated with an up-standing movable scenic background therefor, the said platform and scenic background 45 being so mounted as to be operated in unison in the same direction, and with which preferably there is directly associated a suitable end barrier or backstop 50 means for retrievably catching or stopping the ball when driven by the performer from the platform.

The platform 1 and the scenic background sheet 2 therefor are illustrated as 55 of the endless traveling type, being rotat-

ably mounted upon the horizontal and the vertical rollers 3—4 and 5—6, respectively, but it is obvious that, if a greater length of the scenery were desired, the sheet 2 could be in the form of a roll or web paying off of one of the vertical rollers and being reeled up on the other. 60

The platform 1 and the background sheet 2 are so mounted as to be operated in unison in the same direction, preferably at the same speed, and this is conventionally illustrated simply by the bevel gearing 7 carried by the shafts of the complementary rollers 3 and 5, the shaft of the roller 3 being extended for manual operation by an attached crank 8. It is obvious, however, that equivalent gearing could be supplied at either or both ends of the apparatus, also that the platform and the background sheet may be operated in the same direction either to the left or to the right, and that driving means other than the manually operated crank 8 could be employed, or in fact any suitable means might be employed for causing the platform and the background sheet 70 to be operated in unison or conjointly in the same direction as desired. 75

The supporting bases for the paired rollers 3—4 and 5—6 are preferably assembled as a unit, being illustrated by the solid bottom wall 9 and rear wall 10, respectively, and also illustrated as being permanently joined, although it is obvious that they might be detachably connected and might be constructed in the form of open framework instead of as solid walls. 80 85

Upstanding barrier or backstop means, for catching the driven ball, are provided at either or both ends of the apparatus, said barrier being shown in the drawings as located at the right side and disposed transversely of said endless platform, in substantially spaced relation to the right end thereof, at a position to be obscured from the audience by the closed portion of the stage curtain, or the like, not shown but hereinbefore referred to. 90 95

The said barrier could be mounted entirely separate of the other parts of the apparatus, but it preferably is either a permanently fixed or a detachably assembled part of the unit supporting walls 9—10. It may simply consist of the end wall 11 provided at its inside face with a series of transversely disposed deflecting vanes 12 100 105 110

which are suitably supported in spaced relation to each other and, at their rear edge faces, to the said end wall 11. As actually illustrated, however, the uppermost of these 5 vanes, indicated at 13, is shown wider than the others, and is attached at its rear to the inside face of the end wall 11. Also, a transversely disposed gutter or trough 14 is shown as located towards the bottom of the 10 barrier, and this gutter or trough may be so slightly inclined, if desired, in a direction to discharge either at the front or at the rear of the apparatus. When such specific construction is employed, the deflecting 15 vanes 12 may be conveniently projected from a pair of upstanding bars 15, substantially spaced forwardly of the end wall 11, and which extend between the uppermost 20 vane 13 and the gutter or trough 14. It is not strictly essential, however, that the barrier be constructed with the solid wall 11, as the latter could be in the nature of a frame mounting a net behind said vanes, or it could be a net alone without the 25 emplacement of said deflecting vanes.

It is to be understood, of course, that the rollers 3 and 4 and the rollers 5 and 6 would be spaced sufficiently far apart, in their respective paired relation, as to provide 30 for the display of a substantial portion of the scenery, on the background sheet 2, at all times through the opening in the stage curtain aforementioned, whereas the extreme ends of and mountings for the platform 35 1 and the background sheet 2, as well as the end barrier or backstop means, would all be hidden from the view of the audience by the closed portion of the stage curtain.

It follows that the performer, the top 40 surface of the platform and the scenic background would alone stand out in the setting, as if embowered like a panel, and realism would be enhanced by providing the outer face of the platform 1 with a roughened coating of material in imitation of turf or sward-like ground, or otherwise in simulation of a golf course or the like.

In operation, with the end barrier located 50 at the right side of the apparatus as viewed from the audience and as shown in the drawings, the performer will enter upon the scene at the left side of the platform 1 from behind the drop curtain or the like, and facing the audience from a position towards 55 the left side of the platform, adjacently of the scenic background, he will then place a golf ball or its equivalent, perhaps a softer imitation thereof would be preferable, upon the platform 1 at a suitable 60 position towards the forward portion and to the left of the center thereof, employing a teeing cup for that purpose if so desired.

On making a right hand stroke, therefore, 65 the ball will be driven to the barrier at the

right side, and having so driven the ball the performer will then at once start to walk in a direction towards said barrier.

Immediately upon doing so, the mechanism will be started in motion by an assistant 70 behind the scene, whereupon the platform 1 and the scenic background 2 will travel in unison or conjointly, at an appropriate determined speed, towards the left or in a direction the reverse of the 75 walking movements of the performer, with the obvious resultant appearance of the performer walking the course towards the next position in the field.

After a short period of such motions, and so as the performer supposedly approaches the new position, an assistant, unobserved by the audience, will replace the recovered ball, or another one, upon the moving platform at the right forward side thereof, 85 which will cause the newly placed ball to travel, with the platform, towards the performer but with the appearance of the performer approaching the ball.

When the newly placed ball approximate- 90 ly reaches the desired position relatively to the performer, for the next drive or stroke, the apparatus is stopped by the assistant at the same time that the performer ceases his walking operations, whereafter the cycle of 95 operations may be indefinitely repeated.

It will be obvious that if the performer is to make a left hand driving stroke, with the barrier located at the right side of the apparatus as shown, he would not then face 100 the audience at that time, and the ball would be placed at a position towards the rear of the platform at the left of the center thereof. If, however, the barrier be located at the left side of the apparatus, then the 105 performer and the ball would occupy positions at the right end of the platform and the conditions would otherwise be exactly reversed, as will be apparent, it being further understood that the platform and the 110 scenic background may be operated in either or both directions as circumstances may require.

With the form of barrier as illustrated, the driven ball would be stopped and deflected by and through the vanes thereof, thence falling down within the space between the rear edges of vanes and the wall 11, or the ball would follow an analogous course if a net were employed instead of the solid wall 11, and in either instance if the gutter or trough 14 be also employed, then the ball would be delivered and recovered therefrom at either end of the trough, as desired, dependent upon its direction of inclination.

Although I have thus fully disclosed the improvements, it will nevertheless be understood that I do not restrict myself to all the details exactly as shown and described, ex- 130

cepting as they may come within the terms of the claims made, or equivalent elements or combinations thereof, or as fairly interpreted in the light of the specification if necessary, for it is obvious that alterations may be made without departing from the spirit of the invention. For instance, electrical means may be supplied in substitution for the manually operated means for driving the platform and scenic background, and any suitable means may be employed, if desired, on the outer face of the platform for holding the ball positioned against rolling off of the platform when placed thereon.

15 What I do claim as new and patentable, is:—

1. In theater appliances of the character disclosed, the combination of a portable base support, an upstanding rear support carried by said base support, an endless platform so mounted upon said base support as to be continuously fed longitudinally thereover, a scenic background sheet so mounted upon said upstanding rear support as to be continuously fed therealong longitudinally of said platform, upstanding end barrier means carried by said base support and disposed transversely of said platform, the said barrier means embodying a wall having a transversely disposed trough, along its lower front face, and a vertical series of transversely disposed deflecting vanes thereabove, being adapted for retrieving a ball driven from said endless platform, the said base support, rear support and end barrier means being associated as an assembled portable unit, and means coacting between said endless platform and said scenic background sheet for imparting individual continuous feeding motion, in the same relative directions of movement, simultaneously to the said platform and to the said sheet.

dividual continuous feeding motion, in the same relative directions, simultaneously to the said platform and to the said sheet. 35

2. In theater appliances of the character disclosed, the combination of a portable base support, an upstanding rear support carried by said base support, an endless platform so mounted upon said base support as to be continuously fed longitudinally thereover, a scenic background sheet so mounted upon said upstanding rear support as to be continuously fed therealong longitudinally of said platform, upstanding end barrier means carried by said base support and disposed transversely of said platform, the said barrier means embodying a wall having a transversely disposed trough, along its lower front face, and a vertical series of transversely disposed deflecting vanes thereabove, being adapted for retrieving a ball driven from said endless platform, the said base support, rear support and end barrier means being associated as an assembled portable unit, and means coacting between said endless platform and said scenic background sheet for imparting individual continuous feeding motion, in the same relative directions of movement, simultaneously to the said platform 40 45 50 55 60 65 70 75 80 85 90 95 100

In testimony whereof, I affix my signature.

JOSEPH A. CUNNINGHAM.
